UNITED STATES PATENT OFFICE

FREDERICK R. JEFFERYS, OF CLEVELAND, OHIO, ASSIGNOR TO THE AETNA RUBBER COMPANY, OF CLEVELAND, OHIO, A CORPORATION OF OHIO

ICE-CREAM-CABINET CLOSURE

Application filed September 1, 1928. Serial No. 803,477.

The present invention relates to closure members and more particularly to lids or covers for ice cream cabinets and the like. In such closures, a tight fit is essential in maintaining temperature and the present construction allows such fit to be obtained regardless of slight variation in size of opening or in shape. In addition, the structure provides a tight moisture proof unit which is well insulated. To the accomplishment of the foregoing and related ends, said invention, then, consists of the means hereinafter fully described and particularly pointed out in the claims.

15 The annexed drawing and the following description set forth in detail certain mechanism embodying the invention, such disclosed means constituting, however, but one of various mechanical forms in which the principle 20 of the invention may be used.

In said annexed drawing:—

Fig. 1 is a vertical sectional view on the line 2—2 of Fig. 2; and Fig. 2 is a fragmentary top plan view of the cover.

25 As illustrated, the cover 1 is shown in position in the opening 2 of a cover board 3 of an ice cream cabinet. This cover board is of the usual construction with the circular opening 2 having a substantially vertical side 30 and rounded slightly at the upper edge. The cover proper consists of a ring 5 having a vertical bottom portion 6, an upwardly inclined section 7 with a horizontal top flange 8, a bottom plate 9 is mounted on the ring to 35 fit tightly over the vertical section 6. A cork or other insulating disk member 10 is mounted within the ring which it fits and over the top is a second plate 11 which extends out to nearly the edge of the flange 8. This top 40 plate is secured in position by a knob or handle 12 which is interiorly threaded to receive the threaded end of a bolt 13 which passes through suitable apertures in the two plates and disk 10.

45 The ring 5 is formed of rubber, the bottom portion including the straight portion 6 and the greater part of the inclined portion 7 being formed of hard rubber while the upper 50 part of the ring including the flange 8 and a small portion of the inclined portion being

formed of soft rubber, the two parts being formed into an integral unit by the use of proper hard and soft rubber compounds in the mold when being formed. At the line of division between the hard and soft rubber along 55 the inclined surface, the diameter of the ring is less than the normal diameter of the hole in the cover board of the cabinet and sufficiently less so that the cover will easily enter until the soft rubber portion 20 of the inclined 60 surface will engage with the board. The diameter at the flange is such that the cover has a tight fit and the soft rubber has sufficient resiliency so as to provide for variations in size of opening in the cover board and to 65 allow the cover to be sealed with the flange resting tightly against the top surface of the cover board, thus insuring a seal and reducing the heat loss as far as possible.

By using soft rubber, the cover may be 70 made large enough so as to require a slight amount of force to fully seat it in position and this without danger of breakage of the ring as the hard rubber portion is sufficiently 75 small to fit easily within the cover board aperture. The hard rubber portion provides a ring of fixed diameter to which the bottom plate may be securely attached and a ring which will not distort when the top plate is clamped into position. This construction 80 eliminates any necessity for gaskets or other removable means for sealing the opening and is simple and easy to manufacture and assemble.

85 Other modes of applying the principle of the invention may be employed instead of the one explained, change being made as regards the mechanism herein disclosed, provided the means stated by any of the following claims 90 or the equivalent of such stated means be employed.

I therefore particularly point out and distinctly claim as my invention:—

1. In a closure for ice cream cabinets, the combination of a disc shaped member, an outside supporting ring of hard rubber surrounding said disc, and an integrally formed soft rubber cone shaped portion of larger diameter at the upper portion of said ring, 100 and a soft rubber flange at the top of said ring

extending outwardly from said cone shaped portion.

2. In a closure for ice cream cabinets, the combination of a disc shaped member, an outside supporting ring of hard rubber surrounding said disc, said ring having a cylindrical portion near the bottom, a cone shaped portion of larger diameter thereabove and an outwardly extending horizontal flange at the top, said flange and the upper part of said cone shaped portion being formed of soft rubber, and the balance of said ring being formed of hard rubber integrally united to the soft rubber.

3. In a closure for ice cream cabinets, the combination of a disc shaped member, an outside supporting ring of hard rubber surrounding said disc, said ring having a cylindrical portion near the bottom, a cone shaped portion of larger diameter thereabove and an outwardly extending horizontal flange at the top, said flange and the upper part of said cone shaped portion being formed of soft rubber, and the balance of said ring being formed of hard rubber integrally united to the soft rubber, a bottom plate for said closure surrounding said cylindrical portion, a top plate for said closure engaging the top of said ring, and means to clamp said plates to said ring.

Signed by me this 29th day of August, 1928.
FREDERICK R. JEFFERYS.
